COVER APPLYING MECHANISM FOR CAN
WASHING MACHINESHarry D. Lathrop, Chicago, Ill., assignor to The
Lathrop-Paulson Co., a corporation of Illinois

Application November 30, 1936, Serial No. 113,511

5 Claims. (Cl. 29—84)

This invention relates to a cover applying mechanism for can washing machines. The particular mechanism described herein is especially adapted for applying covers to milk cans after the cans and covers have been thoroughly washed and are ready to be discharged from the machine.

An object of the invention is to provide mechanism which will place a cover on each can as the cans pass forwardly on a conveyor.

Another object is to provide mechanism which discharges a cover toward the opening of a can, the discharging means being operated through contact with each can.

A further object is to provide a mechanism which prevents covers from being discharged except when a can is moved to a position in which it may receive a cover. Other objects and advantages appear as the specification proceeds.

A preferred embodiment is illustrated in the accompanying drawings in which—

Figure 1 is a view in side elevation of my cover applying device, the chute being shown in raised position, and showing a can on the conveyor approaching the end of the chute; Fig. 2, a view similar to Fig. 1, but showing the can moved forwardly to a position under the end of the chute, and showing the chute in lowered or discharging position; Fig. 3, a plan view, the hood and drive connection being shown in section as indicated at line 3 of Fig. 4; Fig. 4, a broken sectional view, the section being taken as indicated at line 4 of Fig. 3, and showing the discharging mechanism in open or discharging position; Fig. 5, a fragmentary sectional view, the section being taken as indicated at line 4 of Fig. 3, and showing the discharging mechanism in closed or non-discharging position; Fig. 6, a view in end elevation showing the discharging mechanism in open position; and Fig. 7, a detail sectional view of one end of the discharging mechanism, the section being taken as indicated at line 7 of Fig. 3.

As illustrated, A designates a frame or support; B, a cover chute; and C, cover releasing mechanism.

The frame A may be of any suitable construction. As here illustrated, it includes a longitudinal conveyor track 10, upon which a conveyor 11, of well known construction, is operated. Conveyor 11 is of the metal chain type and has dogs 12 for propelling the covers forwardly. The frame and conveyor are of the same construction as those now in common use, the portion here shown being used to convey the cans from the machine after they have been thoroughly cleansed. At each side of track 10 is a vertical

standard 13 to which the chute supporting members 14 and 15 are pivotally attached.

The cover chute B, which may be formed substantially of sheet metal, comprises a chute body 16 which includes parallel sides 17 and 18 and a bottom 19 having its forward portion inclined downwardly. Over the downwardly inclined portion of bottom 19 is a liner bottom 20 which has its edges tapered inwardly to a neck portion 21. The forward end of liner bottom 20 is turned down and hooked over the end of chute bottom 19, as shown more clearly in Figs. 4 and 5. Slots 22 extend through chute bottom 19 and liner bottom 20, and receive bolts 22^a by which the supports 14 and 15 are adjustably fastened.

Liner sides 23 and 24 extend along the tapered edges of liner bottom 20 and join with the sides of chute body 16. The liner side 24 is extended rearwardly along chute side 17 and is provided with an upwardly extending flange 24^a which serves as a guard for the covers as they enter this portion of the chute.

The cover releasing mechanism C is mounted at the forward end of the chute and comprises a bar or shaft 25 journaled at each end in bearings 26 secured to chute sides 17 and 18 by bolts 27. Shaft 25 is cut away on one side to form the straight surface 28 which is at approximately an even level with the top surface of liner bottom 20 when the shaft 25 is turned to open position, as illustrated in Fig. 4. Surface 28 may be slightly lower than the top of liner 20, but it should not be at a higher level for in such event it would catch the bottom of the covers as they slide forward and prevent their sliding easily from the chute.

Stops 29 and 30 project from shaft 25 and when the shaft is turned to open position, as shown in Fig. 4, extend substantially vertically. When the shaft is turned to closed position, as shown in Fig. 5, these stops engage the bottom 19 of chute body 16 at each side of neck portion 21.

A jaw 31 is pivotally attached to chute B at bearings 32 by bolts 33. The bottom 34 of jaw 31 extends completely across the chute at the forward end and at its forward edge has a lip 35 directly under shaft 25. If desired, the sides 36 of the jaw 31 may be extended upwardly and provided with a cover 37, which with the sides 36 forms a hood.

The forward portion of jaw 31 is equipped at each side with a toothed sector 38, which is adapted to engage a gear 39, one of which is secured on each end of shaft 25 outside of chute sides 17 and 18. The engagement between sectors 38 and

gears 39 is such that when the jaw 31 is in lowered position, the top parts of sectors 38 engage gears 39 and the shaft 25 is turned to closed position, as shown in Fig. 5; and when the jaw 31 is raised, the lower part of sector 38 engages gears 39 and the shaft 25 is turned to open position, as shown in Fig. 4.

Any suitable means may be provided for raising and lowering chute B. As illustrated, a bracket 10 40 is attached on each side of chute body 16, and a link 41 connects bracket 40 with one end of a lever 42, the other end of which is connected to a fixed arm 43. A rod 44 connected with a central portion of lever 42 is arranged to move vertically and is driven by the power means which drives the conveyor 11.

Operation

After the cans have been completely washed 20 and cleansed, they are carried from the washing machine on conveyor 11. The cans are equally spaced and are pushed forward by dogs 12. Fig. 1 shows a can 45 approaching the end of the cover chute. The covers for the cans, after being thoroughly cleansed, are conducted into chute B and slide down to the forward end where the foremost cover is retained in neck 21 by shaft 25 now held in closed position by the weight of jaw 31. Covers may be introduced into chute B 25 in any suitable way. For example, they may be rolled in on their edges and then caused to fall over on their neck portions. The guard 24^a serves to prevent their bouncing out as they are fed into the chute.

As can 45 moves forwardly on conveyor 11 and comes to a position directly under lip 35 of jaw 31, rod 44 is lowered and allows chute B to be lowered, the supports 14 and 15 turning about their pivoted point. When the lip 35 comes into contact with the top of a can, jaw 31 begins to turn about its pivoted attachment at bolts 33, and as the chute descends further, the gears 39 rotate and move downwardly along sectors 38. This operates to turn shaft 25 to open position 45 and the foremost cover may slide from the chute, as shown at Fig. 2. As the cover moves from the chute, it strikes the edge of the neck of the can and when the can has moved forward a sufficient distance, the cover slides free of the chute and drops into the neck of the can. But before the cover is entirely free from the chute, the rod 44 begins to move upwardly to raise the chute. This causes gear 39 to rotate and move upwardly along sector 38 to again bring the flat side of shaft 25 into vertical position to close the end 50 of the chute just as the first cover has left the chute. Stops 29 and 30 engage bottom 19 to prevent shaft 25 from turning too far and to prevent disengagement of sectors 38 with gear 39.

The above operation is repeated as each can 60 comes into position under jaw 31 and each time a cover is discharged into the neck of the can. If, through any reason the conveyor is not carrying a capacity number of cans, as if every 65 third or every other can is missing, this will not cause covers to be discharged on the floor or will not in any way interrupt the operation of the device. If when the chute is lowered, no can is there to contact lip 35 of jaw 31, the end of 70 the chute will not be opened and no cover will be discharged at that time.

Adjustment may be made by moving the chute forward or rearward, bolts 22^a sliding along slots 22. By this adjustment, the instant at which a can is discharged may be advanced or retarded

and the movement of the chute properly synchronized with the movement of the cans.

While in the foregoing description I have described specific structures in detail, it will be understood that many changes may be made in 5 the construction without departing from the spirit of my invention.

The foregoing detailed description has been given for clearness of understanding only, and no unnecessary limitations should be understood 10 therefrom, but the appended claims should be construed as broadly as permissible, in view of the prior art.

I claim:

1. In a device of the character set forth, a 15 frame, a cover chute movably mounted thereon, means for raising and lowering the chute, a cover release member secured to said chute and consisting of a cylindrical member rotatably mounted in the forward portion of said chute, said member having one side portion cut away so as to provide a top surface substantially flush with the surface of the chute when the cutaway portion is uppermost but presenting an obstruction above the surface of the chute when the cutaway 25 portion is not uppermost, and means carried by the chute and adapted to be actuated by engagement with an object therebelow for rotating said bar to bring the cutaway portion thereof uppermost when an object is engaged.

2. In a device of the character set forth, a 30 frame, a cover chute hingedly supported by said frame, means for raising and lowering said chute, a release member carried by the free end portion of said chute and comprising a cylindrical 35 member rotatably mounted in the end portion of said chute and having a portion thereof cut away to bring the cutaway face portion of the cylindrical member substantially flush with the surface of said chute, and means carried by said chute for engaging an object therebelow to actuate said member to said last-mentioned position, said means causing said cylindrical member to rotate to an obstructing position when the chute is lifted out of engagement with said object.

3. In a device of the character set forth, a 40 frame, a cover chute pivotally secured on said frame, a cover guard having a top wall and two side walls extending over said chute, said side walls being pivotally connected to said chute and having an extension therebelow for engagement 45 with an object when the chute is lowered, a cover release device pivotally supported by the end of said chute, and cooperating means carried by said release device and said cover guard for moving said release member to releasing position 50 when the object is engaged.

4. In a device of the character set forth, a 55 frame, a chute pivotally supported by said frame, means for moving the chute upwardly and downwardly, a release mechanism carried by the end portion of said chute, said release mechanism comprising a rotatable member having a flat side 60 adapted to be aligned with the bottom of said chute and forming a continuation thereof when 65 in releasing position and forming a vertical wall at the end of the chute when in obstructing position, and means carried by said chute for engaging with an object therebelow for actuating said mechanism to releasing and obstructing 70 positions.

5. In a device of the character set forth, a 75 frame, a chute movably mounted upon said frame, means for moving said chute upwardly and downwardly, a cover releasing mechanism associated

with the free end portion of said chute, said mechanism comprising a rotatable member carried by the end portion of said chute providing a flat surface substantially flush with the flat surface of said chute when in releasing position and providing a vertical wall obstructing said

chute above when in obstructing position, and means associated with the end portion of said chute for operating said rotatable member to released position when said means engages an object below said chute. 5
